We claim the ornamental design for a remote control, as shown and described.

DESCRIPTION

FIG. 1 is a top perspective view of a remote control in accordance with our design.

FIG. 2 is a bottom perspective view of the remote control shown in FIG. 1.

FIG. 3 is a right side view of the remote control shown in FIG. 1.

FIG. 4 is a left side view of the remote control shown in FIG. 1.

FIG. 5 is a front side view of the remote control shown in FIG. 1.

FIG. 6 is a rear side view of the remote control shown in FIG. 1.

FIG. 7 is a top view of the remote control shown in FIG. 1.

FIG. 8 is a bottom view of the remote control shown in FIG. 1; and,

FIG. 9 is a rear perspective view of the remote control shown in FIG. 1.

The broken lines in the figures show portions of the remote control which form no part of the claimed design.
